(57) **CLAIM**

The ornamental design for a firearm suppressor, as shown.

DESCRIPTION

FIG. 1 is a front perspective view of the firearm suppressor of the present invention;

FIG. 2 is a side view of the invention of FIG. 1, as seen from the left side of FIG. 6;

FIG. 3 is a side view of the invention of FIG. 1, as seen from the right side of FIG. 6;

FIG. 4 is a side view of the invention of FIG. 1, as seen from the top side of FIG. 6;

FIG. 5 is a side view of the invention of FIG. 1, as seen from the bottom side of FIG. 6; and,

FIG. 6 is a top plan view in elevation of the invention of FIG. 1.

The broken lines represent portions of the firearm suppressor that form no part of the claimed design.
